UNITED STATES PATENT OFFICE.

WILLIAM P. DALRYMPLE, OF CHICAGO, ILLINOIS.

DESIGN FOR AN AUTOMOBILE RADIATOR CAP.

Application filed September 22, 1924. Serial No. 10,851. Term of patent 14 years.

To all whom it may concern:

Be it known that I, WILLIAM P. DALRYMPLE, a citizen of the United States, residing at Chicago, in the county of Cook and State of Illinois, have invented a new, original, and ornamental Design for Automobile Radiator Caps, of which the following is a specification, reference being had to the accompanying drawings, forming part thereof.

Fig. 1 is a plan view of an automobile radiator cap, showing my new design; and

Fig. 2 is a front elevation, showing my new design, and showing also in dotted lines an indicator mounted thereon.

I claim.

The ornamental design for an automobile radiator cap, as shown.

WILLIAM P. DALRYMPLE.
